UNITED STATES PATENT OFFICE.

WILEY N. NASH, OF STARKVILLE, MISSISSIPPI.

RULE AND TRY-SQUARE.

SPECIFICATION forming part of Letters Patent No. 293,497, dated February 12, 1884.

Application filed November 20, 1883. (No model.)

To all whom it may concern:

Be it known that I, WILEY N. NASH, of Starkville, in the county of Oktibbeha and State of Mississippi, have invented certain 5 new and useful Improvements in Drafting-Instruments; and I do hereby declare that the following is a full, clear, and exact description of the same.

My invention relates to improvements in 10 drafting implements, the object being to combine in a single instrument a rule, square, and measure of novel construction and peculiar arrangement.

The invention consists, partly, in combin- 15 ing with a square block or plate of uniform thickness, which forms the corner-piece of the square, peculiarly-beveled arms which contain the scale, and also in details of construction fully hereinafter explained.

20 In the drawings accompanying this speci- fication, Figure 1 is a plan view of the im- plement. Figs. 2 and 3 are views of the be- veled edges of the long and short arms, respect- ively. Fig. 4 is a perspective view.

25 The implement is composed of a corner- piece, A, and two arms, A' A², extending at right angles, the device being formed, prefer- ably, of a single piece of suitable material, such as elastic wood, hard rubber, or thin 30 metal.

The part A is a perfect square of uniform thickness throughout. The arm A' is divided into two triangular surfaces, B D, by a line extending from the point or corner 35 11 on the arm to the corner diagonally op-

posite on the part A. The portion marked D is of the same thickness as the square part A, so that their surfaces are flush at the point where they meet. The part B of the arm A' is beveled uniformly on both sides from the 40 diagonal line referred to the point 6,

where the inner edges of arms A' A² meet, the effect being to form shoulders extending and diminishing from the point 6 laterally across the arm A'. The inner edge of the 45 arm A' is thus reduced in thickness, but its thickness increases uniformly to the point 11.

The outer edge of arm A', extending from the point 8 to 9, is beveled in the manner common to all rulers. The longer arm, A², 50 is divided in like manner into two parts, C and E, the inner part, C, being beveled to- ward the point 6, and shoulders being formed by the square A, in the manner before de-

scribed. The outer edge, extending from 7 to 55 8, has an ordinary beveled edge. The entire outer ruling-edge of the square, extending from 7 to 9, is thus of equal thickness through- out. The inner edge, extending from 10 to 11, is square, and stands at right angles to the surface on which it is used.

On the ruling-edges I lay off inch or metri- 60 cal scales, or both, if desired. A series of distinctive points are formed on the ruler near each edge, and from these the scale-lines ex- 65 tend toward the edge.

I have shown in Figs. 1 and 4, on all the 70 ruling-edges, a series of these points, which are simply small sinks or depressions in the surface, suitably colored, from which the scale- 75 lines extend.

The principal advantages of my construc- 80 tion are that when ruling on the inner edges the edge does not touch the paper, and thus not only permits an ordinary pen to be used without danger of blotting, but also enables 85 the rule to pass partly over an inked line without coming in contact with it. Further, that the shoulders on all sides of part A enable the draftsman to use the edge of the pa- 90 per, however thin, to obtain a perfect right angle, either with the left or right hand edge of such paper.

The advantages of the improved scale have 95 been mentioned, and it may be said, also, that the implement, as a whole, combining the ad- 85 vantages of the try-square, rule, and measure, used separately, is a simple and convenient device, the utility of which will be obvious.

Having thus described my invention, I 90 claim—

1. A try-square having the surfaces of its 95 arms divided into two right-angled triangles, the inner triangular portions being beveled from the diagonal line of division to the right angle 6, substantially as described.

2. A try-square having its outer ruling-edges of uniform thickness and its inner ruling-edges of increasing thickness toward their outer ends, substantially as described.

3. As a new article of manufacture, a try- 100 square having a square corner-piece, A, of uniform thickness, and arms A' A², beveled on both sides thereof, substantially as de- scribed.

WILEY N. NASH.
